[57]

CLAIM

The ornamental design for apertured coverstock for absorbent articles, as shown and described.

DESCRIPTION

FIG. 1 is a top plan view of a portion of a sheet of apertured coverstock for absorbent articles showing my new design; FIG. 2 is a bottom plan view thereof;

FIG. 3 is an elevational view of the lower edge of FIG. 1, the upper edge being substantially identical;

FIG. 4 is a right edge elevational view of FIG. 1; and, FIG. 5 is a cross-sectional view thereof taken on plan 5—5 in FIG. 1.

The left edge elevational view of FIG. 1 is substantially identical to FIG. 5.

The dash-dot-dash broken line showing in FIGS. 1-2 depicts the boundaries of the repeat unit of the claimed design. The dash-dot-dot-dash broken line showing in FIGS. 1-2 depicts the boundaries of a larger portion of the claimed design.
